UNITED STATES PATENT OFFICE.

HARRY HOBSON, OF TOPEKA, KANSAS.

RAILWAY-CROSSING-GATE LAMP AND HANGER.

1,184,097.

Specification of Letters Patent. Patented May 23, 1916.

Application filed February 11, 1915. Serial No. 7,511.

To all whom it may concern:

Be it known that I, HARRY HOBSON, a citizen of the United States, and a resident of Topeka, in the county of Shawnee and State of Kansas, have invented certain new and useful Improvements in Railway-Crossing-Gate Lamps and Hangers, of which the following is a description, reference being had to the accompanying drawings, which

10 form a part of my specification.

My invention relates more particularly to means whereby a lamp or lantern may be properly supported from the usual type of crossing gate employed where railroad tracks make surface crossings, that is, where the tracks and highways cross each other at the same grade; the invention also relating to means whereby the light from the lamp or lantern will be so directed as to be visible 15 from the highway without, however, being visible to the engine-men or crew of trains approaching or occupying the crossing.

One object of my invention is to provide 20 means whereby the lantern will constantly be in a proper vertical position regardless of the position of the crossing-gate, namely whether the gate be in raised or vertical position, so as to clear the crossing, or in a horizontal or closed position, while the rays 25 of light emitted by the lamp or lantern will at all times be in proper direction relative to the crossing.

A further object of my invention is to provide means whereby the shocks, that 30 would be encountered by the lamp or lantern in the operation of the crossing-gate, will be reduced, thereby eliminating any possibility of the light becoming extinguished by reason of jars encountered in the 35 operation of the crossing-gate.

Another object of my invention is to provide means whereby the rays of light, emitted by the lamp or lantern, will be at right angles to the track so as to be constantly 40 visible to pedestrians or individuals on the highway and not visible to the train crew, so that the light may not be mistaken by the latter for a signal light intended to 45 guide the crew in its operation of the train.

50 The purpose of my invention is to provide means of the class herein set forth which will be simple in construction and manipulation and inexpensive in manufacture; the invention possessing other advantages inherent in the device which will be fully un-

derstood from the following detailed description of the construction as illustrated in the accompanying drawings, wherein:—

Figure 1 is a side elevation of my invention showing the same applied to a portion 60 of an arm of a crossing-gate, with the crossing gate shown in closed or horizontal position. Fig. 2 is a similar view of my invention, with the portion of the crossing-gate or arm shown in raised or vertical position. 65 Fig. 3 is a horizontal sectional view taken on the line 3—3 of the lantern in Fig. 1, looking downwardly. Fig. 4 is a side view of one of the lamp or lantern shields, showing the side 70 of the shield which is to come adjacent the lamp or lantern. Fig. 5 is a perspective view of the opposite side or outside of one of the shields. Fig. 6 is a sectional view taken on the line 6—6 of Fig. 3, looking in the direction of the arrows. Fig. 7 is a perspective 75 view of the hanger or fastening portion of my invention, illustrating the same attached to a portion of a crossing-gate or arm. Fig. 8 is a detail view in perspective of a portion 80 of the fastening means or hanger shown in Figs. 1, 2 and 7.

In the particular exemplification of my invention, as illustrated in the drawings, 10 represents a portion of a crossing-gate or arm to which is secured, at a proper point 85 intermediate of its ends, the supporting member or arm 11 preferably made of metal and provided with angular ends 11^a and 11^b. The end 11^a is adapted to be secured to the crossing-gate or arm 10 by any suitable 90 means, as, for example, by bolt or bolts 12, see Fig. 7, so as to maintain the supporting member or arm 11 at right angles to the crossing-gate or arm 10, as shown. In order to provide a firm grip for the securing bolts 95 and their nuts, I prefer to employ a metallic plate 13, see Fig. 1, adapted to be placed intermediate of the nuts on the bolts 12. This plate 13 may either be made integral with or 100 separate from the supporting member or hanger 11.

Secured to the right angular end 11^b of member 11, in any suitable manner, is a plate 14 provided with an off-set 14^a intermediate of its ends so as to provide space intermediate 105 of the free ends of the portion 11^b and the plate or member 14 to receive the intermediate link or member 15. The free ends of the portion 11^b and the plate 14 are preferably provided with corresponding and registering 110

slots extending lengthwise thereof, as shown at 16, see Figs. 1, 2 and 7. The intermediate link or member 15 is provided at one end thereof with right angularly disposed studs 15^a—15^a of a length sufficient to permit them to extend through the elongated slots 16 in the end 11^b and plate or member 14, as more clearly shown in Fig. 7, thus permitting link or member 15 to have considerable movement relative to the fixedly secured portion 11. It is evident from the construction described that the link or member 15 will be free to move lengthwise of the end 11^b and member 14 when subjected to any jar or jolt, and at the same time be permitted to swing into a position substantially at right angles to the direction in which end 11^b and portion or plate 14 extend, as illustrated in Fig. 2, when the crossing-gate or arm is in vertical or raised position.

Secured to the lower or free end of link or member 15 is the lantern or lamp bail-receiving portion or member 17. I have preferred to illustrate the bail-receiving portion as being made separate from the intermediate link or member 15, and have shown this portion or member in the nature of a metallic plate bent backward upon itself so as to provide a loop, with the portion intermediate of the ends thereof of greater width than the ends which are secured to the link or member 15, thus providing proper support for the lamp or lantern-bail whereby undue shifting of the lamp or lantern will be prevented. The bail-receiving member 17 is preferably shown secured to the end of link or member 15 by means of a suitable bolt 18 which passes through registering perforations in the ends of member 17 and the perforations 15^b in the ends of link or member 15; the other end of the bolt 18 being preferably provided with suitable means, such as a butter-fly nut 19, that will enable the bolt being easily secured in place or withdrawn therefrom for the purpose of releasing the member 17 when it is desired to suspend the lamp or lantern in place. The bail-receiving member 17 is preferably so secured to link or member 15 that it may also be free to move or swing independently of link or member 15, thus insuring sufficient freedom for the lamp or lantern and permitting the same to move sidewise irrespective of the other elements or members of the hanger. The connection between member 17 and link 15 may be modified, but should be of such nature as to permit the bail of the lamp or lantern to be easily put into place, and at the same time prevent the accidental displacement of the bail through jars, and so forth.

In order to carry out the further purpose of my invention, I provide a pair of shields 20, 20, similar in construction, which are adapted to be secured to the top rib or wire-

guard of the lantern whereby the glass or chimney is protected. The shields 20, 20 are made of suitable material, preferably thin sheet metal, having the main or body portion 20^a thereof concavo-convex, as more clearly shown in Figs. 3 and 5. The sides of the concavo-convex portion are provided with the wings 20^b, 20^b, arranged to extend at an angle to the main or body portion so as to completely shut off the light from the train crew, or, in other words, shut off the light in a direction parallel with the track, but, at the same time, permitting the light to diffuse in the direction of the highway crossed by the tracks. The shields, as will be readily understood, and as disclosed in the drawings, do not extend entirely about the lantern or lamp, but merely incase the sides of the lantern parallel with the tracks. The main or body portion of the shields, which are preferably of a size to entirely incase the glass or chimney of the lamp or lantern, may be provided with cut-out portions or notches, as shown at 21, and 21^a adapted to receive the loops or portions to which the bail of the lantern is secured and to fit over the wick-controlling member of the burner, respectively, as it is desirable to have the width of the flame presented toward the space between the shields 20, 20, and therefore toward the highway. I have illustrated the shields provided with strips of flexible metal 22, 22, secured to the inner sides of the shields substantially throughout the lengths of the strips, except at the ends thereof. The ends, as shown, are left free so as to permit their being bent into the form of hooks so as to extend about the horizontally disposed wire 23 of the lamp or lantern-guard and over the top rib of the lantern, as shown at 24, see Fig. 6; the shields 20, 20 thus being firmly held in place while, at the same time, permitting them to be removed by simply bending the ends of the strips 22, 22 so as to release them from the wire-guard and top rib of the lantern. The means for securing the shields in place may be differently formed from that disclosed and described; it being essential, however, that the fastening means be of such nature as will permit the removal of the shields for the purpose of giving access to the glass or chimney of the lantern when desired. In the preferred construction of the shields, they may be slightly curved vertically so as to conform more or less to the curvature of the glass or chimney in a vertical direction. The shields 20, 20 may either be made of separate portions of sheet metal, soldered or otherwise secured together, or they may be stamped out of a single sheet. The shields, as is evident from the foregoing, are secured to the sides of the lamp or lantern with which the ends of the bail are secured, in other words, they

are so secured to the lamp or lantern that all rays of light that would be thrown out parallel with the bail of the lantern will be shut off, so as to merely allow the light to 5 shine in opposite directions transversely of the track, that is, in the direction of the highway crossing the track.

In the operation of my invention it is apparent that the lamp or lantern will constantly be maintained in a vertical position regardless of the position of the crossing-gate; that is, the lamp or lantern will extend in a direction parallel with the free end 11^b of the holding member 11 when the 15 crossing-gate 10 is in closed or horizontal position, as shown in Fig. 1, and will extend at an angle to the free end 11^b of the hanger 11 when the gate is either in a vertical or an intermediate position. Furthermore, the 20 intermediate connections of the hanger are such as to reduce the shocks on the lamp or lantern caused in the operation of the crossing-gate when the latter reaches either the vertical position or the horizontal position, 25 thus preventing the lamp or lantern receiving such shocks as might result in extinguishing the light as well as in the spilling of more or less oil.

I have shown and described what I believe to be the simplest and best form of the invention, but it is apparent that certain modifications may be made without, however, departing from the spirit of the invention, and I do not wish to be understood, 35 therefore, as limiting myself to the exact construction shown and described.

What I claim is:—

1. Means of the class described, comprising a member adapted to be secured to a 40 crossing-gate, and a lantern-bail receiving portion, and means intermediate of said portion and said member and yieldingly connected therewith so as to permit the means and said portion to have lateral movement. 45 2. Means of the class described, comprising a member adapted to be fixedly secured to a crossing-gate so as to extend at an angle thereto, and a removable lantern-bail receiving portion having slot and pin connection 50 with the free end of said member so as to permit the lantern to oscillate transversely of said member.

3. Means of the class described, comprising a member adapted to be secured to a 55 crossing-gate so as to extend at an angle thereto, the free end of said member being bent at an angle to the main portion thereof and provided with an elongated slot-way 60 extending lengthwise thereof, and a lantern-holding portion secured in said slot-way so as to move lengthwise of the bent end of said member and to oscillate.

4. Means of the class described, comprising a bracket-member having angularly bent 65 ends, one of which is adapted to be secured

to a crossing-gate while the other or free end is provided with a slot-way, a lantern-receiving portion secured in said slot-way so as to oscillate and have movement lengthwise of said free ends, and means whereby 70 said portion is removably held in place.

5. Means of the class described, comprising a bracket-member adapted to be secured to a crossing-gate and having its free end bent at an angle to the main or body portion 75 thereof, an intermediate member having slot and pin connection with said free end so as to be free to oscillate and to move lengthwise of said end, and a lantern-holding portion 80 removably secured to said intermediate member.

6. Means of the class described, comprising a bracket-member adapted to be secured to a crossing-gate and provided with an angularly bent end, an intermediate member 85 or link connected with said bent end so as to be free to move lengthwise thereof and to oscillate, a lantern-bail receiving loop-member, and means whereby said loop-member is removably secured to said intermediate 90 member.

7. Means of the class described, comprising a bracket-member adapted to be secured to a crossing-gate so as to extend at a right angle therefrom and having its free end bifurcated and provided with an elongated slot 95 extending lengthwise of the bifurcations, an intermediate member provided with oppositely disposed studs or pins adapted to extend into the elongated slots of said bifurcations, and a lantern-bail receiving member removably secured to the other end of said intermediate member, said bail-receiving member being of greater width intermediate of its ends. 105

8. Means of the class described, comprising a supporting-member arranged to be secured to a crossing-gate, a lantern-bail receiving portion removably secured to said supporting member and arranged so as to 110 permit the lantern to have vertical and oscillatory movements, and means removably secured to and arranged to move with the lantern, whereby the rays of light are obscured in directions parallel with the tracks and diffused in directions at an angle to the track. 115

9. In means of the class described, a pair of shields for the lantern, the main or body portions whereof are formed to partially encircle the lantern, said body portions being provided with notches for the passage of the lantern-bail, while the sides of said shields are flared so as to prevent the light 120 being visible in directions parallel with the lantern-bail, and means whereby the shields may be removably secured to the lantern. 125

10. In means of the class described, a pair of shields for the lantern comprising a main or body portion curved to conform to the 130

lantern and having flared sides to constitute wings whereby the light may diffuse in directions substantially at right angles to said body portions but made invisible in directions extending parallel with the sides of the lantern on which the shields are located, and a pair of members secured to

each shield whereby the shields are removably secured to the lantern.

HARRY HOBSON.
